UNITED STATES PATENT OFFICE.

SAMUEL F. SCOTT AND SAMUEL B. BRYAR, OF PITTSBURG, PENNSYLVANIA.

DESIGN FOR A JAR OR BOTTLE.

SPECIFICATION forming part of Design No. 15,813, dated February 17, 1885.

Application filed November 24, 1884. Term of patent 7 years.

To all whom it may concern:

Be it known that we, SAMUEL F. SCOTT and SAMUEL B. BRYAR, citizens of the United States, residing, respectively, at No. 3,507 5 Penn. avenue and No. 209 Denniston avenue, city of Pittsburg, in the county of Allegheny and State of Pennsylvania, have originated and designed a new and original Shape for a Jar or Bottle, of which the following is a specification, the shape being fully represented in the annexed drawings, in which—

Figure 1 represents a perspective view of the jar or bottle, having flat bottom and top, front side perpendicular to its base, and the

sides and back to diverge inwardly from the top to the base. Fig. 2 is a sectional view of the same, these two views being deemed necessary to fully illustrate our design.

What we claim, and desire to secure by Letters Patent, is—

The design for a jar or bottle, as herein set forth and shown.

SAMUEL F. SCOTT.
SAMUEL B. BRYAR.
